CLAIM

The ornamental design for a ladder attached paint can support, as shown and described.

DESCRIPTION

FIG. 1 is a top plan view of a ladder attached paint can support showing my new design;

FIG. 2 is a bottom plan view thereof;

FIG. 3 is a rear elevational view thereof;

FIG. 4 is a front elevational view thereof;

FIG. 5 is a right side elevational view thereof;

FIG. 6 is a left side elevational view thereof; and,

FIG. 7 is a reduced top, front, and left side perspective view thereof, the broken line disclosure of a ladder being for illustrative purposes only and forming no part of the claimed design.

FIG. 1

FIG. 2

*FIG. 3**FIG. 4**FIG. 5**FIG. 6**FIG. 7*
